UNITED STATES PATENT OFFICE.

WILLIAM E. HARDIN, OF MONTEREY, KENTUCKY.

SPOKE-SOCKET.

SPECIFICATION forming part of Letters Patent No. 377,893, dated February 14, 1888.

Application filed September 28, 1887. Serial No. 250,903. (No model.)

To all whom it may concern:

Be it known that I, WILLIAM E. HARDIN, of Monterey, in the county of Owen and State of Kentucky, have invented new and Improved 5 Devices for Uniting Spokes and Fellies of Wheels, of which the following is a full, clear, and exact description.

The present invention relates to a device which is to be applied to the felly of a wheel 10 and to receive and retain the outer end of the spoke, and it is especially applicable for use where a spoke has become broken at its tenon or a felly so split as to not hold the spoke and it is desired to continue its use or to replace a 15 broken spoke without taking the wheel apart; and it consists in the formation or construction of the clip adapted to be applied to the felly and for the reception of the end of the spoke, all substantially as will be hereinafter more 20 fully described, and pointed out in the claims.

Reference is to be had to the accompanying drawings, forming a part of this specification, in which similar letters of reference indicate corresponding parts in all the figures.

25 Figure 1 is a side view of a portion of the fellies of a vehicle-wheel, showing clips constructed under the present invention as applied thereto, some parts being broken away and in section for better illustration. Fig. 2 is a plan 30 view of one side of a clip detached. Fig. 3 is a central longitudinal section through same on line $x-x$ of Fig. 2, and Fig. 4 is a cross-section on line $y-y$ of Fig. 4.

In the drawings, A represents the felly, and 35 B the spokes, and in newly constructing a wheel the spokes, instead of being joined to the felly by mortise and tenon, as at a, may be joined by the employment of the clip C, secured on the inner periphery of the felly by 40 screws or bolts b passing through its body portion D, which has sockets c therein, of form and size to receive the end of the spoke or the tenon formed thereon.

The clips C may be also secured to the felly 45 by rivets passing through holes b² in their overlying lip portions b³ and through the felly from side to side thereof. These clips C may form the means for connecting and securing the sections of the felly, as seen at d in Fig. 1, being 50 of sufficient length to overlap each section a suitable distance, and screwed or bolted to the

sections of the felly by screws passing through such overlapping portions, the felly, and tire.

The sockets c of the clips are of circular, elliptical, rectangular, or other suitable shape, 55 formed by the projections or walls f g, and, as shown, the one end wall and the side walls, f, are formed on and integrally with the body portion, while the end wall, g, is comprised in an angular lug or extension formed upon a 60 plate, E, lying in a groove or way, h, in the body portion D of the clip, said plate being provided with a screw-hole, k, coincident, when the plate is in place, with the screw-hole k² of said body portion, said plate being also pro- 65 vided with an inner or forward extension, l, projecting over or covering the bottom l² of the socket c. The way or groove h, in which the plate E lies and slides for insertion or re- 70 moval, may be provided with inclined or dove-tailed edges, the edges of said plate being correspondingly inclined, thereby insuring greater security of the plate in place.

The utility of a clip of the character de- 75 scribed is found principally in the event of a spoke becoming broken, as at its tenon close up to the felly or a felly becoming split, when, by securing the clip on the felly, the spoke or felly may again be rendered serviceable, or a new spoke may in many instances, by using 80 the present device, replace one broken without the necessity of taking the wheel apart, the advantages of which are obvious. In new work, by using this clip at the joints of the felly-sections the flattening of the wheel at 85 these points will be prevented.

Having thus fully described my invention, I claim as new and desire to secure by Letters Patent—

1. In an article of the character described, 90 the combination, with the body portion adapted to be secured to the inner periphery of the felly having projection or wall, of a plate having projection or wall adapted to lie upon and be secured to said body portion, substantially as 95 and for the purpose described.

2. In an article of the character described, the combination, with the body portion adapted to be secured to the inner periphery of the felly, having projection or wall f and a groove or 100 way, h, of a plate, E, having a projection or wall, g, adapted to lie in said way and to be

secured to said body portion, substantially as and for the purpose described.

3. In an article of the character described, the combination, with the body portion adapted to be secured to the inner periphery of the felly, having projection or wall *f*, of a plate, *E*, having projection or wall *g* and extension *l*, adapted to be secured to said body portion, substantially as and for the purpose described.
- 10 4. In an article of the character described, the combination, with the body portion adapted

to be secured to the inner periphery of the felly, having projection or wall *f* and a groove or way, *h*, of a plate having projection or wall *g* and extension *l*, adapted to lie in said way and 15 to be secured to said body portion, substantially as and for the purpose described.

WILLIAM E. HARDIN.
